UNITED STATES PATENT OFFICE.

WILLIAM H. SAUVAGE, OF NEW YORK, N. Y., ASSIGNOR, BY MESNE ASSIGNMENTS, TO ROYAL RAILWAY IMPROVEMENTS CORPORATION, OF NEW YORK, N. Y., A CORPORATION OF DELAWARE.

LADDER.

Application filed June 10, 1926. Serial No. 115,083.

This invention relates to ladders and more particularly to metallic ladders, especially adapted for use on railway cars, altho it is to be understood that without material modification, it may be used either as a separate unit or attached in sections to the walls of buildings, vessels, mines, silos, chimneys, and the like.

One of the objects of the present invention is to provide a simple, strong and safe ladder preferably made from one piece of rolled steel plate and free from loose parts which are likely to become detached and cause accidents.

15 A further object is to provide a durable, reliable and compact ladder which may be easily and quickly attached in secured position to a car or other wall.

A further object is to provide a ladder 20 of the above character which will permit a more natural use, that is, allowing the user's hands to freely slide up and down the sides instead of grasping the rungs of the ladder.

25 A further object is to provide a ladder free from projections, which are likely to injure the clothing or the hands, and thus permits the person's hands to slide freely and easily over the sides of the ladder when being used.

30 A further object is to provide a ladder which will not only be ornamental in appearance but so shaped as to lessen wind resistance and prevent accumulation of ice and snow when attached to a car.

Further objects such as a practical method 35 of making the same will be in part obvious and in part hereinafter pointed out in connection with the accompanying sheet of 40 drawings illustrating a preferred embodiment of the ladder, and in the several views of which corresponding parts are indicated by similar reference characters.

In the drawings—

45 Figure 1 shows an elevational view of one corner of an ordinary box car to which the ladder is applied.

Figure 2 is a detailed longitudinal sectional view of a form of the ladder.

50 Figure 3 is a detailed perspective view showing a form of attaching means.

Figure 4 is a detailed sectional view showing another form of attaching means.

Referring now to the drawings in detail, 55 5 indicates one side wall of an ordinary box

car which may be made of wood, and 6 indicates the end wall which is now usually made of metal. Both of these walls are provided with vertically disposed ladders for permitting the brakeman to reach the top 60 of the car. The side ladder 7 is provided with a depending auxiliary step 8 within convenient stepping distance from the ground which may be integral with the side ladder if desired. The end ladder 10 is generally shorter and terminates above the buffer at the bottom of the car.

Both of these ladders are preferably made from a single piece of sheet steel rolled into a substantially flat U-shaped cross section as 70 shown in Figure 3. The side edges are curled inwardly towards the wall against which the ladder is positioned to form convenient side hand grips 11 whereby as the user in going up and down the ladder, he may naturally 75 let his hands slide along these curved edges instead of grasping the transverse steps or rungs. These steps 13 are preferably formed by passing this rolled strip of metal thru a die press, which punches or cuts out the 80 opening 12 along three sides or throughout a part of its area and turns inwardly the fourth side or portion 13 to form a wide step which may also constitute a spacing member and attaching means as hereinafter 85 explained. Thus, if desired, this step 13 may be provided with a further bend at right angles thereto, as indicated at 14 in Figure 4. This last portion should be provided with holes thru which bolts or rivets 90

15 may pass for securing the ladder to the metallic end wall 6 of the car, for example, and at the same time be properly spaced therefrom. Any number of steps may have formed thereon the securing portions 14, 95 altho the ladder is advantageously secured to the car wall or other structure by such securing portions being formed on the top and bottom steps only. When the ladder is applied to a wooden side wall, it may be 100 found more desirable to use a filler block, such as shown at 16, Figure 3, thru which securing bolts or fastening devices 17 are adapted to pass. This filling block should be approximately two and a half inches in 105 width, thereby to permit proper setting for the foot on each step 13, and also prevent the fingers from scraping the sides of the car as they slide up and down the sides 11.

In making a ladder of this character, an 110

ordinary sheet metal plate of approximately the size of the completed section is first passed thru one or more shaping rollers to give the desired curvature and finish, after which it is passed step by step thru the punching machine. This automatically cuts the step openings and turns in the uncut part to form the step spacing and attaching portion. This finished article may be 10 most cheaply and inexpensively made.

The ladder herein shown is less expensive to manufacture than the ordinary rung ladder, and has further advantages, such as being safer, easier to climb, and less likely 15 to cause accidents by breakage of parts. It is subject to easy repair in case of damage by collision or "side swipe," as the parts may be easily bent back into shape or the 20 broken parts be repaired by acetyline or electric welds. The average assembled ladder now in use on freight cars is made up of fifteen pieces not including the anchoring or securing devices, while the present ladder is made up of one piece and of any desired 25 length. When the ladder is applied to walls of a building, for example, it is preferably assembled from sections from eight to twelve feet in length, placed one above the other, these pieces being moved thru the rolling, 30 cutting and punching machine in one continuous operation, and then nested one within the other, whereby they may be conveniently shipped and transported, utilizing the minimum amount of space.

35 From the above, it will be seen that the invention is of simple and practical construction, and well adapted to accomplish among others all of the objects and advantages herein set forth.

40 I claim:

1. A one piece metallic ladder of the character herein set forth, having inwardly curved side hand rails and a series of transverse openings forming punched-in steps or 45 rungs, said punched-in portions being partially removed and adapted to form spacing means from the side walls of the structure to which it is applied.

2. A ladder comprising a single elongated 50 piece of rolled metal having a substantially flat U-shaped cross section to form inwardly curved hand grips, and steps formed by punched-out portions in said plate, a material part of each punched-out portion being 55 bent inwardly at right angles to provide a step having a relatively wide flat footing spaced from the wall of the structure to which it is applied, and means associated with the step whereby said ladder may be 60 secured to the wall.

3. A ladder comprising a single elongated piece of rolled metal having a sub-

stantially flat U-shaped cross section to form inwardly curved hand grips, and steps formed by punched-out portions in said plate, part of each punched-out portion being bent inwardly at right angles to provide a step having a relatively wide flat footing spaced from the wall of the structure to which it is applied, and a spacing block 65 70 adapted to be interposed between the back of the ladder and wall.

4. A ladder formed of relatively flat sheet metal and provided with punched portions, each punching being partially cut away and 75 partially bent inwardly at right angles to form a flat step, said inwardly bent portion extending beyond the plan of the ladder thereby to provide a spacing means to hold the ladder away from the wall to which it 80 is secured.

5. A ladder formed of relatively flat sheet metal and provided with punched portions, each punching being partially cut away and 85 partially bent inwardly to form a step, and means associated with said step for securing the ladder permanently to a wall and hold the body of the ladder in spaced relation from the plane of the wall, the sides of the plate forming said ladder 90 being curved inwardly towards the wall, thereby to provide a natural hand slide.

6. A ladder formed of relatively flat sheet metal plate and provided with punched portions, each punching being partially cut 95 away and partially bent inwardly to form a step, and means extending from at least the top and bottom steps for securing the ladder permanently to a wall in spaced relation thereto, the sides of the plate forming 100 said ladder being curved inwardly towards the wall, thereby to provide a natural hand slide, the lower part of the ladder being provided with an auxiliary step integral with the body of the ladder and narrower than 105 the body portion of the ladder.

7. The herein described method of making ladders which consist in rolling a sheet of metal to give it a relatively flat U-shaped cross section, the sides of which constitute 110 hand holds and punching step openings along the central part of said strip to provide steps, bending a portion of the punching inwardly at right angles to provide a 115 relatively wide step extending beyond the plane of the body of the ladder and hand holds, and forming securing portions coacting with at least the top and bottom steps for permanently securing the ladder to a wall or the like.

120 Signed at New York, New York, this 4th day of June, 1926.

WILLIAM H. SAUVAGE.
